BUILDING ROOF PANEL

Norman A. Bellem, Kansas City, James W. Harter, Independence, and Paul E. Swain, Grain Valley, Mo., assignors to Butler Manufacturing Company, a corporation of Missouri

Filed Mar. 17, 1969, Ser. No. 16,270

Term of patent 14 years

Int. Cl. D25—01

U.S. Cl. D54—2

Fig. 3.

FIG. 1 is a top perspective view of a building roof panel showing our new design, the break lines indicating interrupted length;

FIG. 2 is a sectional view taken generally along the line 2—2 of FIG. 1 in the direction of the arrows; and

FIG. 3 is a sectional view taken along the line 3—3 of FIG. 1 in the direction of the arrows, the break lines indicating interrupted width.

We claim:

The ornamental design for a building roof panel, as shown and described.
